HIS ATTORNEY.

UNITED STATES PATENT OFFICE

CHARLES R. VOLZ, OF WALNUT CREEK, CALIFORNIA

PROTECTOR

Application filed March 26, 1928. Serial No. 264,811.

My invention relates to body protectors, and particularly to protectors for use by athletes. This application is a continuation in part of my co-pending application Serial 5 Number 240,951, filed Dec. 19, 1927.

An object of my invention is to provide a protector which will shield a sensitive area from all effect of a blow or pressure.

Another object of my invention is to provide a protector which is easily adjustable to fit wearers of different sizes.

A further object of my invention is to provide a protector which will not lose its shape or effectiveness through use.

15 My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

20 Referring to the drawings:

25 Fig. 1 is a front elevation of a thigh protector embodying my invention. The leg of the wearer is shown in light lines, more clearly to disclose the application of the device.

30 Fig. 2 is a horizontal sectional view and Fig. 3 a vertical sectional view on a larger scale than Fig. 1, the respective planes of section being the lines 2—2 and 3—3 of Fig. 1.

In terms of broad inclusion my invention 35 comprises a shield arched over the parts to be protected. A padded frame beneath the shield and attached to its opposite edges conforms to the body area surrounding the protected region. The cross members or yokes 40 on the frame are resilient, and stress the frame to increase its normal curvature, thus acting as clips which grasp the body of the wearer and tend to hold the shield in position.

45 A strap is preferably provided for holding the protector in place, having one end firmly fixed to the protector. The other end passes through a slot in the edge of the shield and back between shield and frame. Tension on the strap springs the shield slightly and 50 clamps the end securely against the frame,

thus giving easy adjustment, while obviating the use of buckles, which are likely to cause injury.

Protectors thus constructed may be made for almost any part of the body. They differ 55 from the protectors or guards previously known in that they do not merely distribute the force directed to the protected part over a larger area of sensitive tissue, but instead transfer the force to less vulnerable adjacent 60 regions. They are accordingly especially valuable in preventing injury to the shoulder girdle, and for protecting the belly of the long muscles of the thigh from the bruises 65 which cause "charley-horse". I have therefore chosen a thigh protector as the preferred embodiment of my invention for detailed description.

A ring having yokes 6 and side members 7 surrounds the region to be protected and 70 conforms to the area of less sensitive tissue on which the protector rests. Secured to the yokes are resilient curved metal strips 8 preferably of spring steel, which are formed with somewhat greater curvature than the 75 leg they are designed to fit. The rivets 9 are a convenient means of securing the strips 8 to the ring.

The ring and strips together form a frame 80 over which is arched a shield 11, preferably of sheet fiber, opposite edges of which are secured to the side members 7 by the rivets 12. The arched form of the shield holds it clear of the body except at the edges, and any force directed against the shield is diverted to the 85 area upon which the frame rests. The resiliency of the spring strips 8 tends to draw the edges of both frame and shield together, thus increasing their normal curvature. In putting on the protector the edges must therefore be spread apart, and the whole protector 90 grips the body of the wearer and tends to hold itself in position. For comfort and safety a pad 13, preferably of felt, is fastened to the under side of the frame and bears against 95 the body of the wearer.

I prefer to make both frame and shield trapezoidal in general form, extending the outer edge higher on the leg than the inner 100 edge. The protector thus conforms in

length to the muscles it is designed to shield.

The nature of the protection offered by my device makes it essential that it be held accurately in position, and the means for doing this should be adjustable so that the protector

5 may be accurately fitted. To hold it against

the leg one end of a strap 14 of elastic webbing is secured to one edge of the protector. The other end of the strap is passed inwardly

10 through a slot 16 in the opposite edge of the shield and back between the shield and the

frame. Tension on the strap springs the shield in slightly and clamps the strap against the frame. It may, however, be tightened by

15 pulling on the free end 17 or loosened by pulling on the bight so as to release its pressure on the shield. This arrangement gives a

strap which is quickly and easily adjustable, without the use of buckles.

20 The protector is suspended from a belt 18, which may be provided especially for the purpose, or may be integral with a hip pad. An

apron 19 is secured to the upper yoke of the frame. Felt padding 21 is stitched to the

25 inner side of the apron, which has a row of eyelets 22 in its upper edge. A lacing 23

passing through the eyelets; and a similar row 24 in the belt holds the apron and pro-

20 tector in place, and by proper adjustment of

the lacing the protector may be nicely positioned to give maximum protection to the wearer.

An addition to the advantages of my pro-

25 tector already set forth is its ability to hold

its shape until completely worn out, where

the ordinary type, constructed of leather or

fiber without the spring yokes, is warped by

the action of perspiration and heat and so

becomes useless.

30 I claim:

1. In a protector, an arched shield, and a

resilient yoke attached to said shield and

stressing said shield to increase its normal

35 curvature.

2. In a protector, an arched shield, and a

resilient yoke attached adjacent its ends to

said shield and stressing said shield to in-

crease its normal curvature.

3. In a protector, an arched shield, and a

40 resilient frame adapted to conform to an area

surrounding the region to be protected and

attached to and stressing said shield to in-

crease its normal curvature.

4. In a protector, an arched shield, and a

45 resilient frame adapted to conform to an area

surrounding the region to be protected and

attached to opposite edges of said shield

and stressing said shield to increase its nor-

mal curvature.

50 5. In a protector, an arched shield, and a

supporting frame attached to said shield,

said frame comprising a ring adapted to con-

form to an area surrounding the region to be

protected, and a spring member secured

thereto.

6. In a protector, an arched shield, and a

supporting frame attached to said shield, said

frame comprising a ring adapted to conform

70 to an area surrounding the region to be pro-

ected, and a curved leaf spring secured

75 thereto.

7. In a protector, an arched shield, a frame

secured to opposite edges of said shield, and

a strap having one end secured to said pro-

75 tector and the other end releasably gripped

between said shield and frame.

8. In a protector, an arched shield having

a slot in one edge thereof, a frame attached to

said shield and underlying said slot, and a

strap secured at one end to said protector and

so passing through said slot and between said

shield and frame.

9. In a protector, an arched shield, a re-

silient frame attached to said shield and

adapted to grip the body of the wearer, and a

strap secured at one end to said protector and

passing between said shield and said frame.

In testimony whereof, I have hereunto set

my hand.
